UNITED STATES PATENT OFFICE.

EDWARD F. ROSS, OF NEWARK, NEW JERSEY, ASSIGNOR TO THE PERFECT GOLF BALL COMPANY, OF NEW YORK, N. Y., A CORPORATION OF MAINE.

METHOD OF MANUFACTURING GOLF-BALLS.

No. 801,610.

Specification of Letters Patent.

Patented Oct. 10, 1905.

Application filed August 28, 1905. Serial No. 276,040.

To all whom it may concern:

Be it known that I, EDWARD FLETCHER ROSS, a citizen of the United States, residing in Newark, in the county of Essex and State of New Jersey, have invented certain new and useful Improvements in Methods of Manufacturing Golf-Balls, of which the following is a specification.

This invention relates to golf-balls and the manufacture of the same, and has for its object to provide an improved construction and process of making the core of the ball, this being of the class in which the core is built up of windings of sheet-rubber stretched closely to its elastic limit.

In making this class of balls it has been found practically very difficult to accomplish the winding of the strip, generally of rubber, with a sufficient amount of tension therein at the extreme central portion of the core, since in the winding operation, which is ordinarily performed by hand, a releasing of the tension occurs in the middle portion of the core in beginning the winding of the strip upon itself, so to speak, this release occurring before the core has become of large size, the result being that in the finished core the central portion thereof consists of rubber pressed together until it is "solid," while it still remains in an untensioned state or condition. By means of my present improvement I am able to accomplish the required high tensioning of the rubber in the extreme middle portion of the core, with the result that a core is obtained in which practically all of the rubber is not only under high pressure, but also is in a tense condition before the outer and excessive degree of pressure is brought to bear thereon. It should be remembered in this connection that it is deemed important in the making of high-class golf-balls of the character referred to that even the middle portion of the core shall be homogeneous with the outer portions thereof and that the rubber in the middle portions shall consist of material which is at the same time drawn tense, close to the limit of elasticity, and is then subjected to heavy external pressure by the many superposed windings of rubber similarly conditioned.

In the drawings accompanying and forming a part of this specification, Figure 1 repre-

sents a golf-ball, showing a form of embodiment of the present improvement. The ball is shown partly in elevation and partly in central section. Fig. 2 is a perspective view of a strip of elastic material prepared with the preliminary step—namely, the massing together of the material; and Fig. 3 is a perspective view showing the first convolution of the elastic strip about the massed-together material.

In accordance with my present improvement in beginning the winding of the strip I prepare the strip, which is preferably of the tapered form illustrated, by forming a hard relatively taut drawn knot 7 in one end thereof, which serves the double purpose of constituting a small nucleus on which to begin the winding of the strip and at the same time constitutes a gripping element integral with the strip, whereby to obtain the resistance necessary for stretching the strip close to the knot for getting that part of the rubber under high tension at the time it is wound. The winding being thus begun, as at 9, under high tension is then readily accomplished or continued and is here indicated in a general way by 10 until the entire strip is wound up to form the core 11. In this connection it should also be remembered that it is particularly necessary that the entire core should be formed of a single continuous strip of rubber, for one reason, among others, that it is very important to avoid making any part of the core of rubber that is not in a condition both tense and under pressure, thus avoiding any local areas in the core in which the rubber may have a lesser aggregate resilient power than in other parts of the finished core. Such a defect would, it is well known, tend to destroy the reliability and efficiency of the finished ball, which will have a suitable shell or cover 12, and impair the aim or direction of the flight of the same.

Having thus described my invention, what I claim is—

1. That improvement in the art of making golf-balls which consists in tensely binding together a portion of a strip of thin elastic material and then tensely winding said strip about the same.

2. That improvement in the art of making

golf-balls which consists in tying a close knot in the end of a rubber strip and then tensely winding said strip about the knot.

3. That improvement in the art of making
5 golf-balls which consists in tying a hard knot in the end of a comparatively wide strip of india-rubber and then tensely winding said strip about the knot.

4. That improvement in the art of making
10 golf-balls which consists in tensing and binding together a portion of a strip of rubber and then tensely winding the strip about said tensed and bound portion.

5. A playing-ball having a core comprised of a rubber strip tensely wound about a hard 15 knot tied in the end of the strip.

6. A playing-ball having a core comprised of a strip of elastic material tensely wound about an integral center piece composed of tensed and bound portions of the strip. 20

Signed at Nos. 9 to 15 Murray street, New York, N. Y., this 26th day of August, 1905.

EDWARD F. ROSS.
